UNITED STATES PATENT OFFICE.

PATRICK CONNOLLY, OF BROOKLYN, NEW YORK.

FITTING FOR TUBS AND SINKS.

1,416,172.

Specification of Letters Patent. Patented May 16, 1922.

Application filed April 18, 1919. Serial No. 291,057.

To all whom it may concern:

Be it known that I, PATRICK CONNOLLY, a citizen of the United States, residing at Brooklyn, in the county of Kings and State 5 of New York, have invented certain new and useful Improvements in Fittings for Tubs and Sinks, fully described and represented in the following specification and the accompanying drawings, forming a part of 10 the same.

The general object of my invention is to improve and simplify the supply, overflow and drain fittings for bath- and laundry-tubs and sinks and at the same time to do 15 away with objectionable features of fittings of other forms. More particular objects are to provide an overflow for laundry-tubs and to combine this with the supply fitting in a compact, convenient and economical manner; and to provide a fitting which is adapted 20 for use in either bath or laundry-tubs, or sinks, without change, or with few and simple modifications.

To accomplish these and other objects and 25 to realize structural and operative advantages sufficiently pointed out hereafter, a physical embodiment of the invention, generally described, comprises a metal body or casting adapted to be located on a wall of 30 a tub, sink, or similar toilet or laundry appliance, and provided with water-supply connections and faucets, and also provided with an overflow passage or passages leading to the bowl of the tub or sink, and with 35 means for connection of a waste conduit for carrying the overflow to the waste pipe of the house system. The fitting is in some cases arranged to be located in a suitable recess provided in the wall of the tub or sink, and 40 in such cases may be provided with flanges to overlie adjacent portions of said wall both to assist in securing the fitting in position and for artistic effect. An embodiment of the invention also includes, in certain cases, 45 special formation of the tub or sink body to provide suitable recesses and holes therein, to properly accommodate the fitting and piping.

The characteristics of the invention and 50 the nature of variations in structure which may be made to adapt it for use in different toilet and laundry appliances will be best understood after a more particular explanation of certain representative embodiments 55 of the invention shown in the accompanying drawings. After considering these embodied-

ments, it will be understood how other modifications may be made within the principles of the invention, and I do not limit myself to details except as claimed.

Fig. 1 is a vertical section through a laundry-tub, in a plane parallel to one of its ends, with a fitting embodying one form of my invention in position.

Fig. 2 is a vertical section, enlarged, in a central plane of a central wall or partition of the tub of Fig. 1.

Fig. 3 is a section on the line 3—3 of Fig. 2.

Fig. 4 is a section on the line 4—4 of Fig. 2.

Fig. 5 is a perspective detail of a corner of a sink or wash-stand showing a somewhat modified form of my fitting in position.

Fig. 6 is an enlarged sectional detail of the same.

Fig. 7 is a transverse section of a similar fitting, modified, however, to adapt it to a combined sink- and laundry-tub.

Fig. 8 is a vertical transverse section of a bath-tub, showing in position a modification of my invention adapted especially to bath-tubs.

Fig. 9 is a vertical section of the same structure in the plane of the tub wall.

Fig. 10 is a top plan of a part of a tub wall, showing a fitting set into a recess formed therein.

Fig. 11 is an enlarged sectional detail of a modified form of bath-tub fitting.

Fig. 12 is a vertical section in a transverse plane of the tub, showing another modification of the invention especially adapted to bath-tubs.

Fig. 13 is a vertical section of the same in a plane of the tub wall.

Fig. 14 is a top plan view of a bath-tub with one form of my fitting in place, the form of the tub being in this case modified in certain ways.

Fig. 15 is a side elevation of the tub of Fig. 14.

Fig. 16 is an enlarged fragmentary transverse section through the specially formed wall of a tub.

Domestic laundry-tubs have customarily been provided with faucets and connections for hot and cold water and with drain plugs and pipes, but it has not been customary to provide such tubs with overflow fittings except in the form of detachable "stand-pipes"

to co-operate with the drain opening, and except in some cases where two or more of the tubs are arranged substantially as a unit with partitions separating the tubs from each other, these partitions have been 5 pierced at a suitable overflow level so that overflow from one tub would run into the next, and if the drain plug happened to be out in that tub, the overflow would be properly disposed of. But evidently if the drain 10 plugs in both of the tubs of such a unit were left in, there was no provision for overflow beyond the capacity of the tubs.

My invention provides a suitable overflow 15 structure for tubs of this class, which is preferably combined with the supply- or faucet-fitting; also an arrangement by which one combined supply- and overflow-fitting may serve for two adjoining tubs of a laundry- 20 tub or sink-unit; and the invention also provides for locating the combined fitting and the necessary piping on, in, or adjacent to a side, front or back wall of a tub- or sink-structure, whereby the necessity for placing 25 the tub away from a wall, to permit piping to be placed between the tub and the wall, is avoided, with advantages understood by persons familiar with the art.

Figs. 1 to 4 inclusive show a laundry-tub 30 unit comprising two tubs A and B separated by a partition 20. The upper surface 21 of the partition is located considerably below the tops of the front wall 22, the rear wall 23, and the end walls (not shown), and 35 a filler piece 24, which may be of wood, or other suitable material, is placed on top of the partition and secured by suitable means, such as bolts 25. The filler piece affords a convenient and suitable support for the 40 attachment of a wringer.

A fitting F, which in connection with the special formation of the tub and the necessary piping embodies my invention in one form, is located on the partition 20 between 45 the rear end of the filler piece 24 and the back wall 23 of the tub. The fitting proper consists of a body 26 enclosing water chambers 27 and 28 for cold and hot water respectively, and an overflow chamber 29, usually located between the other two. In one 50 form of the invention, as shown in Fig. 2, the bottom of the overflow chamber is considerably below the bottoms of chambers 27 and 28, and the central part of the body 55 26, in order to accommodate the chamber 29, is formed with a downward extension 30.

The under surfaces 31 of the bottom walls of chambers 27 and 28 are arranged to rest upon the upper surface of partition 20, and 60 the partition is formed with a recess 32 to accommodate extension 30 of the fitting. The upper surface 33 of the fitting is usually arranged to be flush with the upper surface of the filler piece 24, and to assist in 65 holding the fitting in position and securing

it against lateral movement, it is preferably provided with side flanges 34 extending flush with each side of the fitting around its side and bottom edges, except at the rear side 35 where the fitting abuts against the 70 rear wall 23 of the tub.

Supply pipes 36 and 37 pass up through holes 38 and 39 provided for them respectively in the partition 20, and the upper ends of these pipes are screwed into suitably 75 tapped holes in the bottoms of the supply chambers 27 and 28 respectively.

Each side of the fitting is provided with suitably tapped holes 40 and 41 communicating with the chambers 27 and 28 respectively, and into these holes are screwed the faucets 42 and 43 for hot and cold water respectively. The faucet holes may preferably be located in bosses 44 formed on the outer faces of the fitting. 85

The overflow passage or passages leading from the tubs may be in the form of one or more holes or other suitable openings 45, passing through the outer walls of the extension 30 of the fitting and communicating with the overflow chamber 29 therein. These holes or overflow passages are located at a level in respect to the tub somewhat below the upper surface 21 of the partition 20, so that the water level in the tubs is 95 kept below the bottom of filler piece 24. The bottom wall of the extension 30 is bored and tapped to receive the threaded upper end of overflow pipe 46, which passes up through a hole 47 provided for it in the partition 20. 100

The spouts 48 of faucets 42 and 43 are usually inclined from the vertical toward the center of the tubs somewhat, as best indicated in Fig. 3, to facilitate the filling of 105 buckets or other receptacles which may be placed in the tubs for that purpose.

Figs. 5 and 6 show a modification of the fitting just described, especially suitable for sinks, in which the fitting F is placed in 110 one of the side walls 50 of the sink S, usually close to the back wall 51. The shape of the body and the arrangement of the chambers, and the supply and overflow pipes, and overflow passage, are substantially 115 the same as above described, except that in this modification the faucets 52 are not connected to the sides of the fitting, but instead the fitting is bored and tapped through its upper surface to receive pipes 120 54, 55, which communicate with the hot and cold water chambers 27 and 28 respectively, and faucets 52 are screwed into elbows located at the upper ends of these pipes. This arrangement provides proper means for filling the sink up to the overflow level when a plug is provided to close the bottom drain opening, and also provides for locating the faucets at such an elevation that they may be easily used to fill buckets or pitchers 125 130

placed in the sink, and to further facilitate the filling of said receptacles; the spouts 48 of the faucets are inclined inwardly as described in connection with the laundry-tub 5 arrangement.

In the adaptation of the fitting to sinks or the like, as shown in these figures, the wall of the sink is formed with a recess 56 to receive the fitting, which has side flanges 34 10 to overlap adjacent parts of the sink wall in substantially the same way, and for the purposes previously described.

The overflow passage or passages 45 are arranged as in the previous structure, except that in this case, where there is only a single sink, the passages are formed through the outer wall of extension 30 communicating with the overflow chamber 29 only at the inner side of the fitting. These 20 overflow openings are located, as clearly indicated in Fig. 5, at a suitable distance above the bottom of the sink to maintain the proper depth of water usually desired in a sink for dish washing and similar purposes. 25 It has heretofore not been customary to provide kitchen sinks with overflow openings connected to the waste pipe, so that when the drain openings were plugged to fill the sinks, the risk of overflow was always involved by failure to fully shut off the water or to remove the drain plug at the proper time.

My invention may conveniently be adapted to use in a combination appliance, such 35 as a combined sink and wash-tub, sufficiently indicated in Fig. 7. In this appliance, the laundry-tub 60 is separated from the sink 61 by a partition 62, and my fitting F² is located in a suitable recess in this partition 40 near the rear wall or apron 63 of the combination appliance. The fitting is constructed substantially as shown in Figs. 1 to 4, inclusive, with faucets 42 at the side of the fitting toward the tub, but the sides 45 of the fitting toward the sink are left without apertures to receive faucets, or if such apertures are present they are plugged, and faucet connections are provided at the top of the fitting as in the structure of Figs. 50 5 and 6, and pipes 54 are screwed into these apertures and faucets 52 are carried at the tops of these pipes with their spouts 48 inclined inwardly toward the sink.

My invention is also advantageously 55 adaptable to bath-tubs. One modification of the fitting applied to a tub suitably adapted for it is shown in Figs. 8 and 9. The fitting F is located in a recess 70 formed near the upper edge of one of the tub walls, 60 which is usually the front wall of the tub, since my invention is especially adapted for tubs intended to be set into or against the wall at the back and one end, or to be set in an alcove so that the back and both ends 5 of the tub are directly against the wall. In

such cases considerable difficulty has been experienced in locating the supply and drain connections, and usually it has been impossible to locate these properly in respect to the tub so that they are at the same time 70 accessible for repair and replacement without breaking into the wall surface or tiling.

The present adaptation of my invention provides for properly locating the faucets and overflow connection in a convenient location on the front wall of the tub and so that the piping is not buried in the walls or 75 behind tiling.

The recess 70 is usually formed in the inner side of the tub wall so that the outer 80 surface of the wall is left continuous at the normal height as indicated at 71, Figs. 8 and 10. Hot and cold water chambers 72 and 73 are formed in the fitting F near the ends thereof, and the hot and cold water 85 pipes 74 and 75 respectively pass up through holes 76 provided for them in the tub wall and are screwed into bored and tapped holes in the bottoms of the chambers 72 and 73 respectively. 90

Between the chambers 72 and 73 the fitting is provided with a space or opening 80, which in this form of the invention extends through it from top to bottom for the accommodation of the overflow fitting. An 95 overflow casing 82 extends through opening 80 and through the hole 84 in the tub wall provided for it, to a point near the bottom of the tub, where it is connected to the upper end of a branch of a T-connection 85. 100 Within the overflow casing is overflow pipe 86, the lower end of which is provided with a rubber sleeve 87 or other suitable valve, arranged to cooperate with a valve seat 88 formed in the T 85. The lower end of the 105 T is secured to the house waste pipe 89, and the remaining branch 90 of the T is connected by pipe 91 and elbow 92 with the usual drain fitting 93 in the bottom of the tub. At the top, the overflow pipe 86 is 110 provided with an operating knob 94 and a pin and slot connection 95, as usual, with the overflow casing 82. At a suitable point below its upper end, the overflow pipe 86 is 115 provided with overflow openings 96. When the knob 94 is properly rotated, the overflow pipe 86 drops in the usual way so that valve 87 closes the seat 88, to retain water 120 in the tub up to the level of the top of overflow pipe 86. As the tub fills, water 120 passes up through the overflow casing until it reaches the level of the overflow openings 96, whereupon the water passes out through the pipe to waste pipe 89, thus limiting the water level in the tub. When the knob 94 125 is properly rotated and raised, valve 87 is raised from its seat and water passes out directly from drain fitting 93 to the waste pipe 89.

The fitting F is preferably provided with 130

top flanges 100 overlapping adjacent surfaces of the top of the tub wall and with side flanges 101 adjoining adjacent parts of the inner surface of the tub wall, and 5 preferably the lower edge of bottom of the fitting is somewhat above the overflow level, as shown in Fig. 8.

The inner wall of the fitting is bored and 10 tapped to receive faucets 102 communicating with the hot and cold water chambers 72 and 73 respectively.

In some cases, unless the thickness of the 15 tub wall is made greater than ordinary, the remaining thickness of the wall at 103, 15 opposite the overflow casing 82 when the wall is suitably apertured to receive the casing, is quite small, and in some cases this 20 may result in spoiling a certain percentage of the tubs in molding and firing them, or 25 in a certain percentage of breakages after they are completed. To avoid this difficulty, in some cases the form of my fitting, and the form of certain of the apertures in the tub to accommodate it, may be changed.

25 As shown in Fig. 11, the central aperture 105 in the fitting may be flattened and elongated, or in a specific form, may be, as shown, in the form of a rectangle, and the cross-sectional shape of the overflow casing 30 82, or at least the upper end of it where it fits into the opening 105, may be shaped to conform with the shape of the opening 105, as indicated at 106. The overflow pipe 86 may in this case be round, if desired, as in 35 Figs. 8 and 9, since this pipe may adjoin the casing 106 closely on two sides, as ample space is provided between the pipe and the casing on two other sides toward the ends of the casing, as clearly indicated in Fig. 40 11. By this arrangement a sufficient thickness of the outer wall of the tub is left as indicated at 107, Fig. 11, to prevent difficulty in manufacture or subsequent breakages.

45 A modified form of tub fitting is indicated in Figs. 12 and 13. This modification provides for the overflow opening to be located near the top of the tub wall, and the fitting proper is, therefore, quite similar to the 50 sink fitting previously described in connection with Figs. 5 to 7. The parts in Figs. 12 and 13 are identified by the same characters as in Figs. 5 to 7, and the construction and arrangement will be understood by 55 reference to previous description. The usual drain fitting 109 is provided in the bottom of the tub, and this is connected to the overflow pipe 110 by a T 111.

60 In some cases, to avoid reducing the remaining thickness of the tub wall by forming passages for the pipes therein and at the same time to avoid the flattening of the overflow space in the fitting, the outer contour of the tub wall may be modified, as

shown in Figs. 14 and 15, by providing 65 vertically arranged enlargements of the wall. In a particular example, semi-cylindrical vertical projections 120 are provided at one or both ends of either or both sides of the tub and these will usually correspond in number to the pipes which pass 70 up through the tub wall at those points, so that apertures may be made in the wall for the pipes, and yet, by reason of the projections, the remaining thickness of the walls 75 will be as great as may be considered desirable. These projections may be provided at both ends of the tub for symmetry and decorative effect, although usually a recess 80 to receive the fitting and holes through the tub wall to receive the pipes need be provided at only one end of the tub, when the enlargements 120 are provided on one side wall of the tub only; and when the enlargements are provided at both ends of both 85 side walls, as shown in Fig. 14, the apertures to receive the fitting and pipes will usually be provided only at the left-hand end of each wall as the tub is viewed in that figure, the enlargements 120 at the right-hand end of the two walls being provided merely for symmetrical effect. In this arrangement by placing either side of the tub 90 against the wall, as may be desired, either a right-hand or a left-hand arrangement of 95 the faucet and overflow fitting is provided for. Enlargements may be provided in the tub wall at other places if desired for the purpose indicated, for instance, on one of the end walls.

100 In many cases it may be desired to conceal the recesses, as shown in Fig. 16 by entirely enclosing them within the tub wall in the process of manufacture, the external portions 130 and 131 of the walls at the top and inner sides of the recesses, respectively, being left thin, so that when it is desired to place the supply and overflow fitting at one particular end of the top wall, the thin walls 130 and 131 at that point are broken 110 away and the fitting put in place. When so placed, the flanges 100 and 101 of the fitting (of the form shown in Figs. 8 and 9, for example) overlap adjacent surfaces of the tub wall and conceal any ragged edges 115 due to breaking away parts of the wall. The surfaces of the tub wall concealing the other recess will then, of course, be left undisturbed. In this form of tub the holes for the pipes will be formed at both ends of the 120 tub, only one set being used.

What is claimed is:

1. A fitting for tubs, sinks and the like, formed of a casting shaped to fit in a recess in the body of a wall of a tub or sink and having a flange to extend over the face of the tub or sink wall, said fitting comprising a supply chamber and an overflow chamber,

- the supply chamber being formed with an inlet opening in the bottom thereof and with an outlet opening for receiving a faucet, and the overflow chamber being formed with 5 an outlet opening in the bottom thereof and with an inlet opening in the side thereof to communicate with the tub or sink on which the fitting is placed.
2. A fitting for tubs, sinks and the like, 10 formed to fit in a recess in the top of a partition wall of a tub or sink, and comprising a supply chamber and an overflow chamber, the supply chamber having an inlet opening and having outlet openings in opposite sides 15 thereof for faucets to discharge on opposite sides of the partition wall, and the overflow chamber having an outlet opening in the bottom thereof and inlet openings in opposite sides thereof for receiving overflow 20 from both sides of the partition.
3. A fitting for tubs, sinks or the like, consisting of a body formed to fit in a recess in the top of a wall of a tub or sink, and comprising two supply chambers and an 25 overflow chamber located between the supply chambers, the supply chambers having bottom connections for supply pipes and having also connections for faucets, and the overflow chamber having a bottom connection 30 for an overflow pipe and a lateral overflow passage to establish communication between said chamber and a tub or sink on which the fitting is placed.
4. In a tub, sink or the like, the combination 35 with a wall of the tub or sink of a fitting located thereon and comprising a supply chamber and an overflow chamber, the overflow chamber having an overflow opening communicating with the bowl of 40 the tub or sink, a faucet connected with the supply chamber and directed into the tub or sink, a supply pipe passing up through said wall and connected with the bottom of said supply chamber, and an overflow pipe 45 passing up through said wall and connected to the bottom of said overflow chamber.
5. The combination with a tub or sink 50 having a wall provided with a recess, of a fitting adapted to be located in the recess and comprising two supply chambers and an overflow chamber located therebetween, faucets connected with the supply chambers and directed into the bowl of the tub or sink, the overflow chamber being provided 55 with an overflow passage communicating with said bowl, supply pipes passing up through said wall and connected with said supply chambers, and an overflow pipe passing up through said wall and connected 60 with said overflow chamber.
6. The combination with a tub or sink 65 having a wall provided with a recess, of a fitting adapted to be located in the recess and comprising two supply chambers and an overflow chamber located therebetween,
- faucets connected with the supply chambers and directed into the bowl of the tub or sink, the overflow chamber being provided with an overflow passage communicating with said bowl, supply pipes passing up through said wall and connected with said supply chambers, and an overflow pipe passing up through said wall and connected with said overflow chamber, said fitting being provided with edge flanges adapted to overlap adjacent parts of said wall. 70
7. In appliances of the class described, the combination of a fitting comprising supply chambers and an overflow chamber, the central part of the fitting having a bottom extension to accommodate a part of said overflow chamber, a bowl structure comprising a wall formed to receive the fitting and having a recess to accommodate said fitting extension, said wall being formed with apertures leading to the bottom of the fitting, and supply pipes and an overflow pipe passing through said apertures and connected to the fitting and having communication with said chambers, said overflow chamber having 80 a lateral aperture arranged to communicate with said bowl to take overflow therefrom. 85
8. In appliances of the class described, the combination of a fitting comprising supply chambers and an overflow chamber, the central part of the fitting having a bottom extension to accommodate a part of said overflow chamber, a bowl structure comprising a wall having a main recess to receive the body of the fitting and having a secondary recess 90 to accommodate said fitting extension, said wall being formed with apertures leading to the bottom of the fitting, and supply pipes and an overflow pipe passing through said apertures and connected to the fitting and 95 having communication with said chambers, said overflow chamber having a lateral aperture arranged to communicate with said bowl to take overflow therefrom. 100
9. The combination with a sink or the like, 105 of a fitting located on a wall thereof and comprising supply chambers and an overflow chamber, an overflow passage leading from said overflow chamber to the sink bowl, supply and overflow pipes leading up 110 through said wall and connecting with said supply and overflow chambers respectively, faucet pipes connected to the top of the fitting and communicating with said supply chambers, and faucets thereon discharging 115 into the bowl. 120
10. The combination with a sink or the like having two bowls separated by a partition wall, of a fitting located on said wall and comprising supply chambers and an 125 overflow chamber, an overflow passage leading from each side of said overflow chamber to one of the adjoining bowls, supply and overflow pipes leading up through said wall and connecting with said supply and over- 130

flow chambers respectively, faucets on one side of said fitting communicating with said supply chambers and discharging into one of said bowls, faucet pipes connected to the top of the fitting and communicating with said supply chambers, and faucets thereon discharging into the other bowl.

In testimony whereof, I have hereunto set my hand in the presence of two subscribing witnesses.

PATRICK CONNOLLY.
